UNITED STATES PATENT OFFICE.

ELIZABETH T. HINCKS, OF CAMBRIDGE, MASSACHUSETTS.

SAND TOY.

1,174,068.

Specification of Letters Patent.

Patented Mar. 7, 1916.

Application filed July 29, 1915. Serial No. 42,652.

To all whom it may concern:

Be it known that I, ELIZABETH T. HINCKS, a citizen of the United States, residing at Cambridge, in the county of Middlesex and 5 State of Massachusetts, have invented an Improvement in Sand Toys, of which the following is a specification.

This invention has for its object the construction of a sand toy especially adapted 10 for small children to play with in the sand.

The invention comprehends essentially a flexible bag shaped to simulate the distinctive object, such for instance as a rabbit, said bag having a slit at the top, and a flexible 15 funnel attached at its smaller end to the margin of the slit, with which it is co-extensive, its flexibility adapting it for external and internal arrangement, and also admitting of holding the object in upright 20 position and of opening the slit to enable the bag to be filled with sand, so that the formation of the object which the bag is intended to simulate will be produced. As a necessary adjunct to my device, I attach 25 thereto, by means of a flexible connection, a spoon or other implement by which the bag may be filled with sand.

Figure 1, is a side elevation of a sand toy embodying my invention. Fig. 2, is a 30 transverse vertical section of the same, taken on the dotted line 2—2. Fig. 3, is a view illustrating the method of filling the toy with sand.

The bag 10, here shown, is made of cloth 35 and composed of several component parts, cut and secured together to simulate a rabbit, which is the distinctive object here shown for illustrating my invention. In this instance, in addition, eyes and ears and a tail 40 are attached to the bag as accessory elements. Other distinctive objects, than the rabbit here shown, will naturally suggest themselves.

The bag has a slit 12 at the top, and a funnel 45 14 of cloth is attached at its smaller end to the margin of the slit, being co-extensive therewith. Said funnel, it will be observed, is flexible like the bag. In lieu of employing cloth other suitable flexible 50 material may be employed. The flexibility of the funnel permits it to be projected ex-

ternally, as shown in Fig. 3, and to be tucked into the bag, out of sight, as shown in Fig. 1. When arranged externally it will be used as a handle to hold the object in upright position, and also to open the slit to permit of the bag being filled with sand, and also to direct the sand into the bag. When arranged internally it is not only concealed but may serve as a closure for the 55 opening when the bag is filled. A spoon 16, is provided which is connected with the bag by a flexible cord, tape, or ribbon 18, which connecting-means is of suitable length to allow the manipulation of the spoon while filling the bag with sand; and said spoon when made of a length somewhat shorter than the length of the bag, may be placed bodily in the bag for shipment, the bag at such time being flattened, as shown in Fig. 2. The 60 spoon, however, may be made of any size.

I claim:

1. A sand toy consisting of a flexible bag shaped to simulate a distinctive object, having a slit at the top, a flexible funnel attached to the margin of the slit, and co-extensive therewith, its flexibility adapting it for external and internal arrangement, for holding the object in upright position and for opening the slit, and for forming a closure therefor.

2. A sand toy consisting of a flexible bag shaped to simulate a distinctive object, having a slit at the top, a flexible funnel attached to the margin of the slit, and co-extensive therewith, and a spoon connected with said bag by a flexible connection.

3. A sand toy consisting of a flexible bag shaped to simulate a distinctive object, having a slit at the top, a flexible funnel attached to the margin of the slit, and co-extensive therewith, and a spoon connected with said bag by a flexible connection, said spoon being shorter than the length of the bag, to enable it to be placed therein.

In testimony whereof, I have signed my name to this specification, in the presence of two subscribing witnesses.

ELIZABETH T. HINCKS.
